Jeffrey D. Moy

(57) **CLAIM**

The ornamental design for an automatic cleaner for swimming pools, as shown and described.

DESCRIPTION

1. Automatic cleaner for swimming pools

1.1 : Front

1.2 : Top

1.3 : Right

1.4 : Left

1.5 : Back

1.6 : Bottom

1.7 : Perspective

The broken lines in the drawings depict portions of the automatic cleaner for swimming pools that form no part of the claimed design.

1 Claim, 7 Drawing Sheets
